UNITED STATES PATENT OFFICE

102,263

DESIGN FOR A COMBINED GARAGE STOOL AND TOOL TRAY

Edwin D. Ely, Troy, Pa.

Application August 29, 1936, Serial No. 64,631

Term of patent 3½ years

To all whom it may concern:

Be it known that I, Edwin D. Ely, a citizen of the United States of America, residing in the city of Troy, county of Bradford, and State of Pennsylvania, have invented a new, original and ornamental Design for a combined Garage Stool and Tool Tray, of which the following is a specification, reference being had to the accompanying drawing, forming part thereof.

In the drawing:

Fig. 1 is a perspective view of the article showing my new design; and

Fig. 2 is a side elevation thereof.

I claim:

The ornamental design for a combined garage stool and tool tray, as shown.

EDWIN D. ELY.
